WILHELM B. BRONANDER, OF MONTCLAIR, NEW JERSEY, ASSIGNOR TO AMERICAN MACHINE & FOUNDRY COMPANY, A CORPORATION OF NEW JERSEY

FOLDING MECHANISM FOR PACKAGING MACHINES

Application filed February 5, 1930. Serial No. 426,106.

This invention relates to improvements in folding mechanisms for packaging machines of the type in which an inner wrapper and an external pouch or label sheet are folded to form a container for packaging cigarettes or other articles. The main object of the present invention is to provide folding mechanism for this purpose which does the folding in a simpler manner, has fewer parts, and requires a lesser number of folding stations and less time than prior machines for the same purpose.

Another object is to so position and fold the wrapper and label sheet that though certain folding operations are dispensed with, the finished container has the same appearance as prior containers made with a greater number of folding operations. Still another object is to provide for folding adjacent flaps of both the inner and outer sheets as a unit thereby eliminating certain folding operations, at the same time providing a surface on the inside of the outer sheet which is not shielded by the inner sheet against receiving paste or being otherwise sealed.

Another object is to provide folding mechanism in which there is no scraping of the foil ordinarily used for forming the inner wrapper. Another object is to provide folding mechanism capable of substitution in the above mentioned type machine for operation by the operating means already provided therein so as to obtain the above objects without requiring any extensive reconstruction of the machine. Another object is to accomplish the above without locking the flaps at the closed end of the pouch so that the cigarettes may be inspected from the bottom without necessitating repackaging.

In packaging machines of this type at present employed, such for instance as that disclosed in application No. 283,758, filed June 8, 1928, by the present applicant and in a corresponding British Patent No. 328,310 to the American Machine and Foundry Company, a tin foil wrapper is cut from a roll and applied to one of a plurality of symmetrically arranged arbors carried by a revolving turret, and the folding of this wrapper is completed, except the closing of one end, before

the paper pouch, which forms the label, is applied, thereby necessitating ten separate folding operations, including the feeding of the foil and of the label, performed at six different stations of the turret, before the container is completed.

By the present arrangement, the tin foil wrapper and paper pouch are folded on the arbor at the same time and as a unit, so that only seven separate operations at four turret stations are required to achieve the same result. Thus the number of folding stations can be decreased or a larger number of idle stations for drying the seals provided, and a faster simpler machine is produced.

With these and other objects not specifically mentioned in view the invention consists in certain constructions and combinations which will be hereinafter fully described and then specifically set forth in the claims hereunto appended.

In the accompanying drawing, which forms a part of this specification and in which like characters of reference indicate the same or like parts, Fig. 1 is a somewhat diagrammatic end elevation of a packaging machine arranged in accordance with the invention; Fig. 2 is a detail side elevation partly broken away on line 2-2 of Fig. 1; Fig. 3 is a detail side elevation, on line 3-3 of Fig. 1; Fig. 4 is a side view, on line 4-4 of Fig. 1, of the third working station, C; and Fig. 5 is a side view, on line 5-5 of Fig. 1, of the fourth working station, D.

In carrying the invention into effect, there is provided a series of traveling mandrels together with means at one station for associating a first sheet with one of said mandrels, folders for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel. In the best constructions said instrumentalities include means operating to position said second sheet in offset relation to said first sheet to cause

the second sheet on completion of folding to hide the seam of the first sheet. Preferably the said means operate to position the sheet with a flap overhanging the forward end edge of the mandrel and said instrumentalities include a device for folding said flap on the end of the mandrel prior to association of the second sheet with said mandrel.

The method employed in forming a container in accordance with the invention consists in providing a mandrel of the shape desired, partially wrapping a first sheet in trough formation about the front and sides and overhanging an end of said mandrel, and wrapping a second sheet also in trough formation about front and sides of said mandrel with one side flap thereof projecting beyond the adjacent first sheet flap so as to hide the seam of the first sheet, and folding the overhanging end flaps to close the container end.

Referring now to the drawing, the construction selected for illustration is shown in connection with the packaging machine disclosed in the above identified application to which reference is made for details not here shown since only so much of the prior machine is shown as is deemed necessary to a ready understanding of the present invention.

The turret 10 of the packaging machine is driven intermittently in synchronism with the working parts of the several folding devices and carries a number of symmetrically spaced hollow mandrels 11 of the same shape as the container to be made. With each of these mandrels is associated two movable arms 12 and 13 carrying respectively, clamp plates 14 and seam pressing strips 15 and 16, the construction and operation of which are fully disclosed in the above mentioned application.

At the first turret station A (Fig. 1) the tin foil F, preferably paper lined, is fed from a reel not shown by feed rollers 18, through vertical guides 19, in order to associate the tin foil or first wrapper sheet with one of the mandrels, whereupon a lining sufficient for forming one container is cut off by the knife 20. The vertical feeding of the wrapper material here is advantageous because gravity aids feeding and positioning of the sheet. The cut wrapper sheet is then held against the front wall of the mandrel 11 by the clamp plate 14 which closes just before the foil is severed, which clamp serves to hold the foil in proper position during subsequent travel of the mandrel and folding of the sheet thereabout.

The overhanging side flaps of the foil sheet are folded in trough formation against the sides of the mandrel by stationary folders including rods 21 placed on opposite sides of the path of travel of the mandrels 11 between the working stations A and B. As the

mandrel arrives at station B, stationary brushes 22 bear against the upturned sides of the foil wrapper sheet thereby laying them smooth and folding them out of the way while a second label or pouch forming sheet P is fed horizontally from a magazine 23 containing cut sheets by a sheet transfer 25 having horizontally reciprocating movement from the magazine to a position under the front of the mandrel as shown in Figs. 1 and 3. Separate horizontal feeding of cut sheets is desirable in this machine because the separate sheets always have their printing in proper register and the separate sheets are more easily supported when horizontal. The transfer device as shown in Fig. 3 reciprocates endwise of the mandrel, and is positioned to deliver the sheets in offset relation with respect to the wrapper sheet already on the mandrel so that one flap thereon will project beyond the corresponding flap of the first or foil sheet as shown at Station C, in Fig. 1. After transfer of this sheet P the clamp 14 located in the clearance between the bars of the transfer 23, which was open to receive said sheet P, closes again and thereby holds the sheet in proper offset relation, as already described.

As the mandrel 11 arrives at station B, the flap overhanging the forward end edge of the mandrel is struck up and folded on the mandrel end (Fig. 3), by a folder 24 which is preferably stationary but which may be oscillated in more refined constructions, if desired.

The importance of this folding operation by the element 24 will be apparent when it is noted that without such folding the several end flaps of the outer sheet would be shielded and any paste applied in the usual manner would be located only on the inner wrapper thus leaving the last end flap of the outer sheet unpasted. By folding as described, the last folded end flap of the outer sheet may be pasted and thus the end sealed despite the unitary folding of the adjacent first and second sheet flaps as hereinafter described. This tucking of the forward end flap of the inner wrapper also serves to so separate the two wrappers so that the two will not be locked against inspection by unsealing the outer sheet and separating the two.

Upon leaving station B, the mandrel enters between the stationary circular folding plates 26 which fold up the overhanging sides of the label sheet P as the mandrel passes between them, so that the package arrives at station C with the sides of both the foil wrapper F and of the label sheet P turned up in trough formation about the front and sides of the mandrel. These upturned sides are laid smooth on the mandrel sides by the stationary brushes 27, and their overhanging ends are prevented from sagging down too low by the stationary rods 28. The turret

having come to rest at station C, first the arm 29 and then the arm 30, Fig. 4, moves towards the mandrel, thereby folding down the ends of wrapper sheets F and P against the rear side of the mandrel by means of the 5 folding plates 31 and 32, respectively, these plates being pivoted to their actuating arms and guided in parallel motion by suitable means well known in the art such as those shown in the above mentioned application. 10 As will be seen in Fig. 1, the arm 30 carrying the folding plate 32 is moved in by a reciprocating link 30c connected to a lug 30b on the arm. An arm 30a connected to the arm 30 15 carries a protection which engages a shorter arm 29a secured to the arm 29, which arm is pulled against the arm 30a by a spring 29b. Since the arm 29a is shorter, giving greater leverage than arm 30a folding plate 31 acts 20 first laying the left hand flaps under the right hand flaps.

Paste is applied to the edge of the longer label sheet side flap by any suitable means not shown, so that the second folding operation at this station seals the side of the package. It is noted that offsetting sheet P with 25 respect to sheet F so that the outer right hand side flap (station C, Fig. 1) projects beyond the corresponding inner side flap, not 30 only serves to conceal the seam of the inner sheet on completion of folding but lays the edge portion of the projecting flap open to paste application and provides a sealing surface, thus eliminating otherwise serious objections to the simple unitary folding of inner and outer sheets. 35

As the plates 31 and 32 are retracted to their neutral position after having folded the side flaps against the rear side of the mandrel, the clamp strips 15 and 16, which were raised off the mandrel by the actuating arm 13 on entering the station, return to their clamping position in which they remain until the package is ready to be discharged from 45 the turret, thus keeping the sealed seam under pressure until the paste has dried.

At station D the folding of the container about the sides and one end of the mandrel is completed by folding the overhanging end 50 flaps. First, the side tuckers 33 move towards each other close to the forward end of the mandrel, Fig. 5, whereby the side end flaps of both wrappers F and P are tucked in over the mandrel; and then the folding plate 34 is moved forward, in the direction of the turret rotation, by the arm 35, thus folding as a unit the adjacent rear end flaps of both wrappers over the end of the mandrel. In leaving this station, the remaining front 55 end flap of the label sheet P, to the inside edge of which paste has been applied, engages with the stationary roller 36 held in fork 37. This folds said front end flap over the previously folded rear end flap and completing the bottom fold of the package which 60

now forms a complete open container sealed at the bottom and along one of its sides, ready to be filled, by inserting cigarettes or other articles through the hollow mandrel discharged from the turret mandrel, and 70 closed.

The filling and ejecting operations are performed at station A, which is the starting station as well as the finishing station. As the mandrel with the completed pouch package returns to station A, a cam operated plunger 38, shown in Fig. 2, and more fully disclosed in the above mentioned application, one of which is associated with each mandrel, inserts a properly arranged bundle of cigarettes C, prepared in another part of the machine, into the open rear end of the mandrel and pushes the same through the mandrel and out at the front end, see dotted lines in Fig. 2, thereby stripping the pouch from the mandrel and filling it at the same time. The plunger 38, after expelling the filled package, remains at the front or delivery end of the mandrel and serves as a backing for the ensuing folding operations at stations 80 85 B, C, and D, being withdrawn from the mandrel, after the latter has left station D and before it returns to station A, a sufficient distance to permit the cigarettes C to enter between it and the rear or receiving end of 90 95 the mandrel.

Thus though the folding of the two sheets has been greatly simplified by folding a number of the adjacent flaps thereof as units, a container for forming a package has been 100 formed which is identical in outward appearance and which is as thoroughly sealed as packages produced by completely folding first an inner and then an outer sheet. In view of the above, further description of the 105 operation of this device is deemed unnecessary and is omitted in the interest of brevity.

What is claimed is:—

1. The method of forming a container which consists in providing a mandrel of the shape of the container to be made, partially wrapping a first sheet in trough formation about the front and sides and overhanging an end of said mandrel, then wrapping a second sheet in trough formation about the front and sides of said mandrel with one side flap thereof projecting beyond the adjacent flap of the first sheet, folding as a unit the other side flaps of the first and second sheets, thereafter folding as a unit the projecting side flap and the adjacent first sheet flap so as to hide the seam of the first sheet, and folding the overhanging end flaps to close the container end. 115

2. The method of forming a container which consists in providing a mandrel of the shape of the container to be made, partially wrapping a first sheet in trough formation about the front and sides and overhanging an end of said mandrel, folding the overhang- 120 125 130

ing front end flap against the end of the mandrel then wrapping a second sheet in trough formation about the front and sides of said mandrel with one side flap thereof 5 projecting beyond the adjacent flap of the first sheet, folding as a unit the other side flaps of the first and second sheet, thereafter folding as a unit the projecting side flap and the adjacent first sheet flap so as to 10 hide the seam of the first sheet, and folding the overhanging end flaps to close the container end.

3. The combination with a series of traveling mandrels, of means at one station for associating a first sheet with one of said mandrels, means for partially wrapping said sheet about the mandrel, instrumentalities at another station for associating a second sheet 15 with said mandrel, devices for partially wrapping the second sheet about the mandrel, and mechanism operating on both of said sheets as a single unit to complete the folding of said sheets about the sides and one end of said mandrel.

4. The combination with a series of traveling mandrels, of means at one station for associating a first sheet with one of said mandrels, means for partially wrapping said sheet about the mandrel, instrumentalities at another station for associating a second sheet 20 with said mandrel, devices for partially wrapping the second sheet about the mandrel, and mechanism operating on both of said sheets as a single unit to complete the folding of said sheets about the sides and one end of said mandrel.

5. The combination with a series of traveling mandrels, of means at one station for associating a first sheet with one of said mandrels, folders for partially wrapping said sheet about the mandrel, instrumentalities at another station for associating a second sheet with said mandrel, devices for partially 25 wrapping the second sheet about the mandrel, and mechanism operating on both of said sheets as a single unit to complete the folding of said sheets about the sides and one end of said mandrel, said means including a clamp 30 and mechanism operating on both of said sheets as a single unit to complete the folding of said sheets about the sides and one end of said mandrel, said means for successively securing said first sheet against the forward side of said mandrel and said second sheet against the forward side of said first sheet.

6. The combination with a series of traveling mandrels, of means at one station for associating a first sheet with one of said mandrels, means for partially wrapping said sheet about the mandrel, instrumentalities at another station for associating a second sheet 35 with said mandrel, devices for partially wrapping the second sheet about the mandrel, and mechanism operating on both of said sheets as a single unit to complete the folding of said sheets about the sides and one end of said

mandrel, said associating means including wrapper material feeding and severing devices for feeding sheets vertically from a continuous strip to a position in front of the mandrel and said instrumentalities including means for feeding cut label sheets horizontally into a position in front of the mandrel. 70

7. The combination with a series of traveling mandrels, of means at one station for associating a first sheet with one of said mandrels, means for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said means for partially wrapping the sheet about the mandrel operating to hold the first sheet wrapped about the front and sides of said mandrel during the operation of said instrumentalities. 75

8. The combination with a series of traveling mandrels, of means at one station for associating a first sheet with one of said mandrels, means for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said means for partially wrapping the sheet about the mandrel including brushes holding the first sheet against the sides of said mandrels during the operation of said instrumentalities. 80

9. The combination with a series of traveling mandrels, of means at one station for associating a first sheet with one of said mandrels, folders for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said means for partially wrapping the sheet about the mandrel comprising stationary folding elements positioned along the path of travel of the mandrels. 85

10. The combination with a series of traveling mandrels, of means at one station for associating a first sheet with one of said mandrels, folders for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and 90

one end of said mandrel, said instrumentalities including means operating to position said second sheet in offset relation to said first sheet to cause the second sheet on completion of folding to overlap the seam of the first sheet.

11. The combination with a series of traveling mandrels, of means at one station for associating a first sheet with one of said mandrels, folders for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said instrumentalities including a sheet carrier movable to and from a position adjacent the front of the mandrel in which the second sheet carried thereby is offset edgewise with respect to the first sheet to cause said second sheet to overlap the seam of the first sheet.

12. The combination with a series of traveling mandrels, of means at one station for associating a first sheet with one of said mandrels, folders for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said instrumentalities including means operating to position said second sheet in offset relation to the first sheet to thereby provide an overlapping side flap projecting beyond the corresponding side flap of first sheet, and said devices operating to fold the projecting flap subsequent to folding of the flaps on the opposite side of the mandrel.

13. The combination with a series of traveling mandrels, of means at one station for associating a first sheet with one of said mandrels, means for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said associating means operating to position the sheet with a flap overhanging the forward end edge of the mandrel and said instrumentalities including a device for folding said flap on the end of the mandrel prior to association of the second sheet with said mandrel.

14. The combination with a series of traveling mandrels, of means at one station for associating a first sheet with one of said man-

drels, means for partially wrapping said sheet about the mandrel, instrumentalities at another station for associating a second sheet with said mandrel, devices for partially wrapping the second sheet about the mandrel, and mechanism operating on both of said sheets as a single unit to complete the folding of said sheets about the sides and one end of said mandrel, said devices comprising stationary folding elements positioned along the path of travel of the mandrels.

15. The combination with an element of the shape of a package to be formed, of means for wrapping an inner and outer sheet in trough formation about the sides of said element with one side flap of the outer sheet projecting beyond the adjacent side flap of the inner sheet, and mechanism operating to fold as units the adjacent inner and outer sheet side flaps on the element to complete the folding about the sides thereof, said mechanism being arranged to fold the projecting flap and the adjacent inner sheet flap subsequent to the folding of the other side flaps.

16. The combination with an element of the shape of a package to be formed, of means for wrapping an inner sheet about the sides of said element and overhanging one end thereof, a device for folding in one of the overhanging end flaps of said inner sheet, means for folding an outer sheet about the sides and overhanging the end of said element, and mechanism for folding in as units the double end flaps formed by the two sheets, and means for subsequently folding in the remaining single outer sheet flap to complete the end folding.

In testimony whereof, I have signed my name to this specification.
